UNITED STATES PATENT OFFICE.

LAFAYETTE W. JOHNSON, OF JEROME, ARIZONA TERRITORY, ASSIGNOR OF ONE-THIRD TO FRANK C. CLARK, OF JEROME, ARIZONA TERRITORY.

BLOCK.

SPECIFICATION forming part of Letters Patent No. 689,090, dated December 17, 1901.

Application filed April 23, 1901. Serial No. 57,146. (No models.)

To all whom it may concern:

Be it known that I, LAFAYETTE W. JOHNSON, a citizen of the United States, and a resident of Jerome, in the county of Yavapai and Territory of Arizona, have invented a new and Improved Block, of which the following is a full, clear, and exact description.

This invention relates to a block of that class known as "snatch-blocks," in which parts of the framing or shell of the block are movable to permit a rope to be engaged with the sheave without necessitating reeving the rope through the block.

To this end the invention comprises a block with a swivel-eye, serving not only to sustain the block, but also removably to engage the straps or other rigid portions of the structure of the block, so as to hold the rope properly in the sheaves.

20 This specification is a specific description of one form of the invention, while the claims are definitions of the actual scope thereof.

Reference is to be had to the accompanying drawings, forming a part of this specification, 25 in which similar characters of reference indicate corresponding parts in all the views.

Figure 1 is an elevation of the invention, partly broken away and in section. Fig. 2 is a cross-section on the line 2 2 of Fig. 1, and 30 Fig. 3 is a sectional plan view of the device.

a represents the sheaves of the block, which are here shown to be four in number. Obviously the block may be constructed with any number of sheaves desired. The shell 35 or framing of the block is made up of a number of sections b, which are equivalent to the cheek-sections of the usual block, such sections b being rigidly connected together by spacing-blocks c, arranged at their lower end

40 and held in place by tie-bolts d, passing through the spacing-blocks. The sections b have bosses b' thereon, these bosses matching together to form journals for the sheaves a. Passing through these bosses b' is a tie-bolt 45 e, which holds together the various parts.

The block has a central section f, held to the sections b by the tie-bolt e and formed with a socket f', in which is fitted a stud g, extending vertically above the block and having a 50 flange or cap g' at its upper end.

h indicates the eye before referred to, this

being triangular in general contour and being mounted upon the stud g. The eye h has notches h' therein at the point which receives the stud g, and these notches receive corresponding ribs g² on the stud. The ribs g² are arranged at the upper part of the stud, so that when the eye h is drawn upward, as shown by full lines in Figs. 1 and 2, the parts h' and g² are locked together and the eye is 60 incapable of turning on the stud. The eye is held in this elevated position by means of a cotter-pin or other locking device i, which is passed through the stud g and which is removable to release the eye h. By releasing the pin i and dropping the eye h to the position shown by dotted lines in Fig. 1 the eye may be given a quarter-turn, causing it to assume the position indicated by dotted lines in Fig. 3. The upper ends of the sections b of the block are formed with hooks b². These hooks are arranged oppositely at each side of the stud g—that is to say, the hooks b² at one side of the stud are extended oppositely to the hooks on the other side. 75 When the eye h is raised, as shown in Fig. 1, it is engaged with the hooks b², and being held by the pin i it cannot turn. If it be desired to engage a rope with or disengage it from the block, the pin i should be released. 80 This will permit the eye h to drop, and then it may be turned sidewise, so as to disengage it from the hooks b². By this arrangement it will be seen that upon a very simple movement of the parts of the block the sheaves 85 are exposed, so that they may receive the rope or be disengaged therefrom at will. In this connection it should be observed that the lower part of the eye h forms practically a lock-bar, which in moving to and from its 90 normal position closes or opens the block. It is not positively essential that the block be suspended from this lock-bar, since a becket or shackle may be attached to the block at any other point and the part h employed 95 merely as a swinging lock-bar for covering or uncovering the sheaves of the block.

Having thus described my invention, I claim as new and desire to secure by Letters Patent—

1. A block, comprising a body portion having a stud provided with a rib thereon and

also having an upwardly-projected hook, a lock-bar mounted to swing on the stud and capable of engaging the rib, whereby the swinging movement of the lock-bar is prevented, means for holding the lock-bar in engagement with the rib, and a sheave mounted in the body of the block.

2. A block, comprising a body portion provided with a stud, and oppositely-disposed hooks arranged at opposite sides of the stud, sheaves mounted in the block at opposite sides of the stud, and an eye, part of which

forms a lock-bar, said part being pivoted on the stud intermediate the ends of the lock-bar and movably engaging the hooks, for the purpose specified.

In testimony whereof I have signed my name to this specification in the presence of two subscribing witnesses.

LAFAYETTE W. JOHNSON.
